UNITED STATES PATENT OFFICE.

AXEL WASBERG AND WILLIAM W. DARROW, OF CHICAGO, ILLINOIS, ASSIGNEES TO CAMEL COMPANY, OF CHICAGO, ILLINOIS, A CORPORATION OF ILLINOIS.

STEEL DOOR.

Application filed April 27, 1925. Serial No. 25,986.

- The present invention relates to steel doors.
- More particularly the present invention relates to steel doors for freight cars and has for one of its objects the provision of a fabricated door which is of relatively light weight and great strength and which will present a substantially smooth inner surface inwardly of the car.
10. A further object is to provide a fabricated steel door made up of interchangeable parts, whereby if repairs are necessary such repairs may be made at a minimum of trouble and expense.
15. A further object is to provide a fabricated steel door in which the parts are so arranged that rain or other form of precipitation will be effectually shedded, whereby leakage will be prevented.
20. A further object is to provide a fabricated steel door which will present a smooth surface on the interior of a railroad car, which door involves a minimum of parts.
25. A further object is to provide an all metal door particularly adapted for railway box cars and having great strength to resist strains and stresses encountered in service.
30. A further object is to provide a fabricated door of comparatively small parts so that repairs in the way of replacements may be made at small cost and with minimum labor charges.
35. A further object is to provide a steel door having corner pieces or gussets which may be pressed cold into the desired shape without requiring the drawing of large sheets of metal, thereby overcoming the former unsatisfactory features of wrinkled corners.
40. A further object is to provide a steel door which may be readily assembled, which presents a workmanlike appearance both inside and outside of the car, and having the parts so overlapped that rain or other precipitation is efficiently shedded, whereby said precipitation may not seep into the construction of the door.
45. A further object is to provide a steel door wherein all four margins of the door are provided with rolled structural shapes, which may be of great strength to resist
- shocks and which will provide adequate water and burglar protection.
- A further object is to provide a steel door which has rolled structural shapes at the 55 regions at which shocks are most likely to be encountered and which has readily fabricated material at the regions less likely to encounter shocks.
- A further object is to provide an all 60 metal door which may be manufactured at a comparatively small cost.
- Further objects will appear as the description proceeds.
- Referring to the drawings—
65
Figure 1 is a fragmentary side elevation illustrating the side of a car and a pair of steel doors cooperating therewith;
Figure 2 is a fragmentary sectional view taken along the plane indicated by the arrows 70 2—2 of Figure 1;
Figure 3 is a view, on an enlarged scale, of one of the steel doors shown in Figures 1 and 2;
Figure 4 is a sectional view, on an enlarged scale, corresponding to the right-hand door shown in Figures 1 and 2;
Figure 5 is a sectional view, on an enlarged scale, indicating the interfitting 75 means between the two steel doors shown in Figures 1 and 2;
Figure 6 is a fragmentary perspective view illustrating a channel member for connecting together adjacent parts of the structure involving the present invention;
Figure 7 is a sectional view taken along the plane indicated by the arrows 7—7 of Figure 3;
Figure 8 is a sectional view taken along the plane indicated by the arrows 8—8 of Figure 3; and
80
Figures 9 and 10 are perspective views illustrating details of construction.
- The present invention has been illustrated in connection with a car having a main door and a supplementary door in the side wall thereof. When a door opening of ordinary width is required the main door only is opened, the supplementary door remaining in fixed position. The supplementary door may be provided with a movable door jamb, said door jamb being fixed to or de-
95
100

tached from said supplementary door, as preferred. When a doorway of extraordinary width is required the main door, the supplementary door and said door jamb are moved out of closing relationship with the doorway.

Referring first to Figures 1 and 2, the car wall is indicated by the numeral 1, the side plate is indicated by the numeral 2, and the side sill is indicated by the numeral 3. The door jambs 4—4 define a wide doorway, intermediate of the width of which is the movable door jamb 5, which may be moved longitudinally of the car when it is desired 15 to provide an unobstructed doorway of relatively great width. Movable door jambs are well known and need not be described in detail herein. It is sufficient to state that said movable door jamb 5 has means for locking same in a position midway of the door jambs 4—4, which position may be conveniently termed the door-closing position.

The numeral 6 indicates the main door, 25 and the numeral 7 indicates a supplemental door. These doors may be top hung or bottom hung, the manner of hanging being independent of the present invention. According to the illustrated embodiment of the present invention, the supplementary door 7 is secured to the movable jamb 5. Said movable jamb in the illustrated embodiment comprises an angle 8 of structural steel, the reentrant angle of which may receive a timber 9, constituting a nailing strip to which boards may be conveniently nailed when it is desired to use the car for the carrying of grain or other lading in relatively small particles. From an inspection of Figure 2 30 it will be noted that the movable jamb 5 is provided with a Z-bar 10 forming a pocket for receiving the edge of the main door 6. Arranged adjacent to the right-hand jamb 4 is a Z-bar 11 provided with an angle 12 having a flange for receiving a hooked over edge portion of the main door 6. The main door 6 may be provided with the hinged member 14 for engagement with the hasp 14' carried by the movable jamb 5. 35 The sliding retaining member 14'' is adapted to securely hold the hinged portion 14 in locking relationship with the hasp 14'.

Steel doors have been provided in the past, but in so far as applicants are aware 40 said doors have not been entirely satisfactory. Steel doors have been provided made of members which may be fabricated only under rather special conditions, so that repairs have been very costly. According to the present invention, each door is provided at its margins with rolled structural steel shapes which are purchasable in the open market. Said marginal members are very 45 sturdy and are positioned to take the worst of the shocks encountered in service. Con-

nected to said marginal members are a plurality of steel members, all of which may be swedged and machined when cold, so that the cost of manufacture and replacement is relatively low.

The door 6 will be described in detail, it being considered that a description of said door will suffice to enable anyone skilled in the art to understand the invention. Referring to Figures 4 and 7, it will be noted that one marginal edge of the door 6 is defined by the Z-bar 15. The top edge of said door 6 is defined by the Z-bar 16, and the lower edge is defined by the Z-bar 17. The right-hand margin of the door 6 as said door is viewed in Figure 4 is defined by the W-bar 18. It will be noted that one leg, indicated by the numeral 19, of the W-bar 18 is swedged inwardly for the purpose of providing a hook which is adapted to fit over the angle 12 50 carried by the stationary door jamb 4. The structural steel members 15, 16, 17 and 18 are riveted together to provide a rectangular frame, said members having certain of their flanges crimped slightly at the corners of said frame to permit said structural steel members to present plane surfaces on both sides of said frame.

Referring to Figure 8, it will be noted that the structural steel member 16 has riveted thereto the swedged steel member 20. Having in mind that the right-hand side of each of Figures 7 and 8 indicates the outside of the car, while the left-hand side of each of said figures indicates the inside of the car, it will be noted that the swedged steel member 20 is positioned relative to the structural steel member 16 so as to shed rain and other forms of precipitation. Said swedged steel member 20 is bent inwardly 55 toward the rear of the door, that is—toward the interior of the car, and provides a flange 21, which flange 21 extends substantially parallel with the planes provided by the inner and outer sides of the frame provided by the structural steel members 15, 16, 17 and 18. Said flange 21 is secured to the panel 22, which panel is positioned on the inner side of the flange 21. The swedged steel member 20 is located midway of the width 60 of the door, but stops short of the corners of said door. Gussets 23—23 are provided at the two corners, which have overlapping relationship with the swedged steel member 20. Said gussets 23—23 are also swedged to provide flanges 24—24 located in substantially the same plane as the flange 21, overlapping flanges being crimped to 65 permit the positioning of flanges 21 and 24—24 in substantially the same plane. Said gussets are also riveted to the inner side of the frame provided by the structural steel members 15, 16, 17 and 18.

Located below the panel 22 is the channel member 25. Said channel 25 has the upper 70

flange 26 secured to the inner side of the panel 22, said flange being located between the panel 22 and the adjacent panel 27. The lower edge of the channel 25 is flanged, as indicated by the numeral 28, which flange 28 is riveted to the outer surface of the panel 27. Located at the lower edge of the panel 27 is the channel 29, which has the upper flange 30 secured to the inner surface 5 of panel 27, being located between said panel 27 and the panel 31. The lower flange 32 of the channel 29 is secured to the outer surface of the panel 31. The lower edge of the panel 31 has secured thereto the swedged 10 steel member 33, which swedged steel member 33 has the flange 34 located on the inner surface of the panel 31. Said swedged steel member 33 is riveted to the structural steel member 17.

20 Arranged at the two sides of the door 6 are the two gusset plates 35-35, which have overlapping relationship with the gussets 23-23 and the channel member 25. Said gussets 35-35 conform in cross section at 25 their extremities to said gussets 23-23 and channel member 25 and are riveted to same as well as being riveted to the panels 22 and 27 and to the rolled structural steel members 15 and 18.

30 Positioned at the two ends of the panels 27 and 31 are the gusset plates 36-36, having extremities conforming to the corresponding portions of the gusset plates 35-35 and to the channel 29. Said gussets 36-36 are 35 riveted to the panels 27 and 31, the channel 29 the side structural steel members 15 and 18 and to lower corresponding gusset plates 23-23, which are identical in shape with the upper gusset plates 23-23 referred to above. Said lower corner gusset plates 23-23 are riveted to the swedged steel member 33, said lower corner gusset plates and said member 33 being riveted to the remainder 40 of the door to provide a solid job. It will be noted that the lower structural steel member 17 is cut away to provide space for rollers 45 37-37, which may be rotatably mounted in any preferred way.

50 The pockets in rear of the gussets 23, 35 and 36 along the side margins of the door are closed by the plates 38-38. The pockets in rear of the steel members 20 and 33 and their adjoining gussets 23 are closed by other plates 38-38. Said members 38-38 may be crimped at their overlapped end portions, whereby the greater extent of said members 38 along the four margins of the door may lie in engagement with the structural steel shapes 15, 16, 17 and 18.

55 The description of door 6 which appears above will be sufficient for an understanding of the construction of door 7. The invention is not limited to constructions having a pair of doors on each side of the car, but is 60 equally applicable to single doors.

It will be noted that the inside of each of the doors is substantially flat, the overlap between adjoining panels and their strengthening members necessitating only a slight divergence from a perfectly flat condition. The outside of the door with its reinforcing channels presents a workmanlike appearance, and great strength is had per unit of weight by reason of the box girders provided by the members 20 and 33, the 70 channels 25 and 29 and the gussets 23, 25 and 36, together with the backing members 38-38 and panels 27 and 31.

It will be noted that the gussets 23-23 at the four corners of each of the doors are 80 identical in shape and therefore interchangeable, and that the side gussets 35 and 36 adjacent to the two side margins of the door are identical in shape and therefore interchangeable. The matter of manufacture 85 and repair is therefore greatly simplified.

It will be noted that starting from the top of each of the doors the parts are so overlapped that the members closest to the top of the car are lapped on the outside of 90 the member next adjoining at a lower level. By reason of this construction the shedding of rain and other forms of precipitation is readily accomplished.

Though a preferred embodiment of the 95 present invention has been described in detail, it will be clear that many modifications will occur to those skilled in the art. It is intended to cover all such modifications that fall within the scope of the appended 100 claims.

What is claimed is:

1. A steel door for railway cars, including a rectangular frame made up of flanged structural steel shapes of relatively sturdy 105 construction, swedged sheet steel members of relatively light weight secured to said frame, panels of relatively light weight connecting said swedged steel members, and channel members of relatively light weight secured 111 to said panels and to said swedged steel members for providing box girders.

2. A steel door, comprising, in combination, structural steel members including three Z-bars and a W-bar secured together to form a rectangular frame, swedged sheet 115 steel members of a weight such that they may be swedged cold secured to the inner side of said frame, and panels and reinforcing channels of light weight secured to said frame and to said first mentioned light weight sheet steel members for closing said frame.

3. A steel door, comprising flanged structural steel members of relatively sturdy construction connected together to form a substantially rectangular frame, sheet steel members of relatively light weight, said sheet steel members comprising swedged 120 grooved members and panels connected to 125

- gether in overlapping relationship to provide alternately arranged box girders and panels.
4. A steel door comprising flanged structural steel members of relatively sturdy construction connected together to form a substantially rectangular frame, sheet steel members of relatively light weight, said sheet steel members comprising swedged
- 5 grooved members and panels connected together in overlapping relationship to provide alternately arranged box girders and panels, said members being positioned to provide a substantially flat surface on one
- 10 side of said door and a ribbed surface on the other side of said door.
5. A steel door comprising flanged structural steel members of relatively sturdy construction connected together to form a substantially rectangular frame, sheet steel members of relatively light weight, said sheet steel members comprising swedged
- 20 grooved members and panels connected together in overlapping relationship to provide alternately arranged box girders and panels, said frame and said sheet steel members being overlapped from top to bottom of said door in positions to shed rain or other forms of precipitation.
- 25 6. A steel door comprising flanged structural steel members of relatively sturdy construction connected together to form a substantially rectangular frame, sheet steel members of relatively light weight, said sheet steel members comprising swedged
- 30 grooved members and panels connected together in overlapping relationship to provide alternately arranged box girders and panels, said members being positioned to provide a substantially flat surface on one side of said door and a ribbed surface on the other side of said door.
- 35 7. A steel door comprising flanged structural steel members of relatively sturdy construction connected together to form a substantially rectangular frame, sheet steel members of relatively light weight, said sheet steel members comprising swedged
- 40 grooved members and panels connected together in overlapping relationship to provide alternately arranged box girders and panels, said frame and said sheet steel members being overlapped on the outside of said door to shed rain and other forms of precipitation.
- 45 8. A steel door comprising flanged structural steel members of relatively sturdy construction connected together to form a substantially rectangular frame, sheet steel members of relatively light weight, said sheet steel members comprising swedged
- 50 grooved members and panels connected together in overlapping relationship to provide alternately arranged box girders and panels, said frame and said sheet steel members being overlapped on the outside of said door to shed rain and other forms of precipitation.
- 55 9. A steel door comprising flanged structural steel members of relatively sturdy construction connected together to form a substantially rectangular frame, sheet steel members of relatively light weight, said sheet steel members comprising swedged
- 60 grooved members and panels connected together in overlapping relationship to provide alternately arranged box girders and panels, said frame and said sheet steel members being overlapped on the outside of said door to shed rain and other forms of precipitation.
- 65 10. A steel door comprising flanged structural steel members of relatively sturdy construction connected together to form a substantially rectangular frame, sheet steel members comprising swedged
- 70 grooved members and panels connected together in overlapping relationship to provide alternately arranged box girders and panels, said frame and said sheet steel members being overlapped on the outside of said door to shed rain and other forms of precipitation.
- 75 11. A steel door comprising flanged structural steel members of relatively sturdy construction connected together to form a substantially rectangular frame, sheet steel members comprising swedged
- 80 grooved members and panels connected together in overlapping relationship to provide alternately arranged box girders and panels, said frame and said sheet steel members being overlapped on the outside of said door to shed rain and other forms of precipitation.
- 85 12. A steel door comprising flanged structural steel members of relatively sturdy construction connected together to form a substantially rectangular frame, sheet steel members comprising swedged
- 90 grooved members and panels connected together in overlapping relationship to provide alternately arranged box girders and panels, said frame and said sheet steel members being overlapped on the outside of said door to shed rain and other forms of precipitation.
- 95 13. A steel door comprising flanged structural steel members of relatively sturdy construction connected together to form a substantially rectangular frame, sheet steel members comprising swedged
- 100 grooved members and panels connected together in overlapping relationship to provide alternately arranged box girders and panels, said frame and said sheet steel members being overlapped on the outside of said door to shed rain and other forms of precipitation.
- 105 14. A steel door comprising flanged structural steel members of relatively sturdy construction connected together to form a substantially rectangular frame, sheet steel members comprising swedged
- 110 grooved members and panels connected together in overlapping relationship to provide alternately arranged box girders and panels, said frame and said sheet steel members being overlapped on the outside of said door to shed rain and other forms of precipitation.
- 115 15. A steel door comprising a frame made up of flanged structural steel shapes, panels located intermediate of the inside and outside planes of said frame, gussets secured to the flanged portions of said structural steel shapes and swedged to form pockets, and members closing said pockets and se-

cured to said structural steel shapes to provide box girders.

16. A steel door comprising a frame made up of flanged structural steel shapes, panels located intermediate of the inside and outside planes of said frame, gussets secured to the flanged portions of said structural steel shapes and swedged to form pockets, and members closing said pockets and se-

cured to said structural steel shapes to provide box girders, a plurality of said girders being of like shape, whereby to simplify the matter of manufacture and repair. ¹⁰

Signed at Chicago, Illinois this 22nd day of April, 1925.

AXEL WASBERG.

WILLIAM W. DARROW.
